UNITED STATES PATENT OFFICE

142,374

DESIGN FOR A SALT SHAKER OR SIMILAR ARTICLE

Edwin G. Cobelli and Donald N. McDougal,
Miami, Fla.

Application June 27, 1945, Serial No. 120,366

Term of patent 14 years

(Cl. D44—22)

To all whom it may concern:

Be it known that we, Edwin G. Cobelli and Donald N. McDougal, citizens of the United States, residing at Miami, in the county of Dade and State of Florida, have invented a new, original, and ornamental Design for a Salt Shaker or Similar Article, of which the following is a specification, reference being had to the accompanying drawings, forming part thereof.

Figure 1 is a top plan view of a salt shaker or similar article, showing my new design,

Figure 2 is a side elevational view,

Figure 3 is a vertical sectional view therethrough, and

Figure 4 is a bottom plan view thereof.

We claim:

The ornamental design for a salt shaker or similar article, as shown.

EDWIN G. COBELLI.
DONALD N. McDUGAL.
